METAL SUITCASE

Robert B. Wemyss, Louisville, Ky., assignor to
 Reynolds Metals Company, Richmond, Va., a
 corporation of Delaware

Application January 29, 1947, Serial No. 725,136

2 Claims. (Cl. 190—19)

1

The present invention relates to metal suitcases, particularly those formed largely of sheets of aluminum or other metals. In the following specification and claims, the term "suit case" is intended to designate any such equipment permanently usable for the transportation of articles including sample cases, tool boxes, and the like.

The general object of the invention is to provide a suit case of strong construction, excellent appearance and light weight.

The invention will be described with reference to the accompanying drawings, in which:

Fig. 1 is a perspective view of an embodiment of the invention, showing a suitcase in open condition;

Fig. 2 is an end view of the same suitcase in closed condition;

Fig. 3 is a fragmentary vertical cross section through the lower part of the closed suitcase shown in Fig. 2, on line 3—3 of Fig. 6;

Fig. 4 is a fragmentary cross section through the upper part of the suitcase, taken in the same plane as Fig. 3, but showing a modification in which the marginal edges of the two case members are turned inwardly and not outwardly as in Fig. 3;

Fig. 5 shows the parts illustrated in Fig. 3 in their positions when the suitcase is opened;

Fig. 6 is a fragmentary elevation of the suitcase shown in Figs. 1 and 3 viewed from one side thereof; and

Fig. 7 is a sectional view corresponding to that of Fig. 3, showing a modification in that the marginal edges of the two case members are rolled.

In accordance with the invention, the embodiment illustrated in Fig. 1 comprises three primary members 10, 11 and 12, permanently interconnected by hinges 13, see Figs. 3 and 5 to a backbone 10. The latter is formed with an internal reinforcing member consisting of a web 15' which carries a flanged head 16 inwardly of which extends a rib 17.

The primary case members 11 and 12 are preferably of identical construction, forming symmetrical right-hand and left-hand compartments. They may be made of deep-drawn metal, preferably aluminum, and may be provided with a finished and reinforced marginal edge all around as shown by the outwardly turned portions 18 of Figs. 1, 3 and 5, or the inwardly turned portions 18x and 18xx of Figs. 4 and 7, respectively.

The backbone 10 may be integrally cast, or it may be extruded and then bent to form a rectangle and its ends welded together. A por-

2

tion outwardly of web 15' is cut away between points 19 and 20 to accommodate a pair of hinge plates 21 and 22 respectively secured to the members 11 and 12, e. g., by rivets 23 or by welding. To complete the backbone connection a hinge rod is then inserted between the butt ends of the outer heavy portion of member 10 at points 19 and 20 and in the curled hinge areas 13 of the hinge plates. When both compartments are open, these hinges will elevate the backbone 10 to the position shown in Figs. 1 and 5. When the case is closed, the hinges and the ends of rib 14 will be prevented from bearing unduly upon the floor surface by the provision of suitable supporting studs 25, two of which are shown in Fig. 2. These studs also serve to stabilize the suitcase in an upright position.

Locks 26, 27 are disposed on the frame 10, having tongues 28 designed to fit into apertures 29. The tongue of lock 26 is arranged to cooperate with an aperture 31 provided on the case section 11 adjacent the edge 18 thereof, and lock 27 may similarly engage the aperture 32 correspondingly located on case section 12. A handle 33 is secured to the backbone.

The backbone may contain a center panel 34 (Fig. 1) which may be of any suitable material but is preferably made of transparent plastic. When one compartment, say 11, has been filled, this panel may be used to keep the contents in place by swinging the frame into horizontal position and locking the same to section 11 by means of lock 26. When the other compartment, 12, has been packed, the suitcase may then be completely locked by means of lock 27. The panel 34 may also be provided with pockets or flaps (not shown) as is customarily done with inserts and covers of conventional suitcases.

To facilitate opening and closing of the case sections, hand recesses 35 may be provided in the sides of members 11, 12.

It will also be understood that, whereas there is shown a single locking device for securing each case section 11, 12 to the backbone 10, a plurality, e. g., two, may be provided for this purpose. It will be understood that the hinge rod, which is indicated at 24, Figure 5, for example, may be made as an integral part of the web 15x and that spaced slots between the web and the rod portion may be provided for the insertion of the hinge plate ends, the latter thereafter being curled around the rod. As an alternative, the inner portion of the web 15' may be formed as a sleeve to receive the rod, the sleeve being cut 55 away at spaced points to provide clearance pas-

sages for the hinge strips 21 and 22, the latter, in such case, being as to each suitcase member, a plurality of spaced, relatively narrow hinge strips having eyes at their ends for reception of the hinge rod. A suitable method of making the backbone is by casting the same into an integral unit.

Having thus described my invention, what I claim as new and desire to secure by Letters Patent, is as follows:

1. A metallic suitcase comprising two case members and a connecting backbone therefor formed of a unitary metallic member of relatively narrow width and having connected outer and inner walls which are spaced to provide oppositely directed channelways for receiving the margins of the case members, said channelways merging into an inwardly directed rib adapted for the attachment of a pocket-holding division between the two case members when the suitcase is closed, and latching members carried by the backbone for holding the two case members.

2. A metallic suitcase comprising two similar drawn-metal case members, and a connecting

5 backbone therefor consisting of a unitary metallic member of relatively narrow width, the outer portion of which is rounded and integrally joined to a narrow web which inwardly carries a head, thus providing opposed channelways for receiving the marginal edges of the case member, said rounded portion of the backbone being cut away at its base, hinge elements in said cut away portion and connected to the case members, and a hinge pin connecting said hinge members to the back bone.
